176,396

WRAPPING PAPER OR SIMILAR ARTICLE

Walter L. Wolf, Philadelphia, Pa., assignor to Wolf Brothers, Inc., Philadelphia, Pa., a corporation of Pennsylvania

Application August 12, 1954, Serial No. 31,849

Term of patent 14 years

(Cl. D59—2)

FIG. 2

Fig. 1 is a plan view of a wrapping paper showing my new design, a unit being enclosed within the dot and dash lines and repeated as indicated by the extensions beyond the unit boundaries; and

Fig. 2 is an enlarged fragmentary view of the wrapping paper shown in Fig. 1 and shown in an inverted relationship thereto.

I claim:

The ornamental design for a wrapping paper or similar article, as shown and described.
